Primary Examiner — Dominic Simone(74) Attorney, Agent, or Firm — Craig R. Miles; CR Miles, P.C.(57) CLAIM

I claim the ornamental design for a three-toed shoe, as shown and described.

DESCRIPTION

FIG. 1 is a top and right side perspective of a three-toed shoe embodying our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown are included for the purpose of illustrating the unclaimed portions of the article and form no part of the claim.
